2 SHEETS—SHEET 2.

UNITED STATES PATENT OFFICE.

WILLIAM AUSTIN, OF SCRANTON, PENNSYLVANIA, ASSIGNOR OF ONE-HALF TO
MICHAEL W. O'BOYLE, OF PITTSSTON, PENNSYLVANIA.

TRACK-STOP.

1,137,178.

Specification of Letters Patent. Patented Apr. 27, 1915.

Application filed March 30, 1914. Serial No. 828,277.

To all whom it may concern:

Be it known that I, WILLIAM AUSTIN, residing at Scranton, in the county of Lackawanna and State of Pennsylvania, have invented certain new and useful Improvements in Track-Stops, of which the following is a specification.

My invention is an improved track obstruction or stop for use in automatic train stopping systems and the like, and the invention, while of more or less general application, is primarily designed for use in connection with the train stopping system, which forms the subject matter of my application for patent filed March 10, 1914, Serial Number 823,714.

In train stopping systems wherein a controlled track obstacle is engaged by a trip lever on the train, it is necessary to so design the parts as to reduce the liability of breakage or disarrangement, to the minimum. Track stops require to be strongly and durably constructed, constructed as simple as possible, and arranged to gravitate to the operative or danger position in case of any disarrangement or breakage in the mechanism or its connections. It is also necessary to protect the stop and its operating mechanism from the weather so that it may be free from disablement due to climatic conditions.

My invention, therefore, primarily has for its object to provide a device which will fulfil the requirements as nearly as may be.

Generally, the invention comprises standards or supports on which a substantially U-shaped stop arm is mounted to gravitate to the horizontal or danger position, or be held up at an angle of 45 degrees or thereabout in the safety or non-operative position, by the action of electro-magnetic devices suitably operatively connected in the block circuit.

The stop arm is partly counter-balanced and is covered by a water shed housing which, except when the arm is in the danger or operative position, completely houses the arm; the solenoidal magnets which hold the arm up are either directly connected thereto by rod and crank connections, or a counter-shaft may be interposed, if desired, in the connection.

The invention also includes those novel details of construction, combination and arrangement of parts, all of which will be

first fully described and then be specifically pointed out in the appended claims, reference being had to the accompanying drawings, in which:

Figure 1 is a side elevation and part section of the invention, showing its relative location to the signaling semaphore in connection with which it may be employed. Fig. 2 is a top plan view of the same. Fig. 3 is a horizontal section on the line 3—3 of Fig. 1. Fig. 4 is an enlarged horizontal section on the line 4—4 of Fig. 1. Fig. 5 is a vertical cross section on the line 5—5 of Fig. 4. Fig. 6 is a vertical longitudinal section and part elevation showing the invention adapted for use on overhead structures. Fig. 7 is a horizontal section on the line 7—7 of Fig. 6, looking in the direction of the arrow. Fig. 8 is a horizontal section on the line 8—8 of Fig. 6. Fig. 9 is a side elevation showing the invention adapted for use in sub-way structures.

Referring now to the accompanying drawings, in which like numerals and letters of reference designate corresponding parts in all of the figures, 1 represents the standards or supports which are preferably made tubular and are provided with chambered portions 2 to receive the electromagnets 3. The magnets 3 are preferably of the solenoidal type and have cores 4 that serve as armatures and are connected by rods 18 with cranks 16 on the stub shafts 13 on which the U-shaped stop arm 9 is keyed.

At the top, the standards 1 have flanges 5 by means of which the water shed housing 6 is held in position, the housing 6 having a portion 7 removed, so that when the arm 9 is in its horizontal or active position, the front face 10—11 will be exposed to contact by the train carried arm (not shown). The moving of the arm 9 to the horizontal position is arrested by any suitable stop, for instance stops 8 that may be provided on the housing 6. The arm 9 is of the substantial U type and has its bend formed by the bevelled faces 11 and the front face 10 so as to assure an easy operation of the train carried member when it comes in contact with the stop arm.

The stop arm 9 has rearward extensions 19 to receive adjustable counter-weights 20 whereby the arm may be partially counter-weighted, but not enough to prevent the arm from gravitating to the horizontal position

when the magnet 3 is deenergized. The arm 9 is also provided with bosses 12, to receive the stub shafts 13, and keys 14 to key the arm to the stub shafts. Each stub shaft

5 13 has a crank 16 which connects, by a connecting rod 18, with the core 4 of the respective operating magnet 3, and suitable anti-friction bearings 15 are provided in the bearing housing 17 formed in the standard 10 1 as a part of the same, the bearing housing 17 being suitably closed by plugs 21 to prevent access of moisture.

15 22 designates the ordinary type of semaphore support having a magnet chamber 23 and carrying the usual semaphore 24. I have illustrated the relation of the ordinary semaphore to my stop to show the adaptability of the joint use of the two, without interfering with each other.

20 20 In Figs. 6 to 8 inclusive, is shown a slight modification of the invention.

In this form, the construction is arranged for use on overhead structures of the bridge type.

25 36 designates the bridge and 37 the supporting towers or standards therefor.

Suspended beneath the bridge 36 are the supporting columns 1^a, which have flanges 5^a to support the housing 6^a, and which are 30 provided with bearing members 17^a to receive the ends of the shaft 13^a on which the stop arm 9^a is mounted.

8^a designates the stops which correspond to the stops 8 in Fig. 1.

35 35 In this form of the invention, vertical extended columns 25, having magnet chambers 27, are provided to project upwardly from the bridge 36. The magnets 3^x are located in the chambers 27 and have their cores or 40 armatures 4^x connected, by rods 28, to the cranks 29 on a counter-shaft 30, which is mounted in suitable bearings 31 carried by the upper ends of the standards 25.

The standards 25 also have flanges 26 to support the supplemental housing 35 which includes the arms 32 that carry the adjustable counter-weights 20^x and are thus keyed at 34 through their hubs 33 to the shaft 30.

50 55 The counter-shaft 30 is also provided with a crank 18^y which is connected by a connecting rod 18^x, that extends through a middle column 39, to the crank 16^x on the shaft 13^a, whereby the shaft 13^a and the counter-shaft 30 may be moved in unison.

55 60 In Fig. 9, is shown a further modification, which is quite similar, however, to the structure shown in Fig. 1, differing therefrom essentially only in the omission of the housing 6 and the provision of a recess or chamber 38, which performs the function of the housing 6 in so far as that function is required in a subway structure.

In operation, the magnets 3 or 3^x, as the case may be, are connected in circuit with 65 any automatic block system to operate in

unison with the indicating semaphore, and upon deenergization of the magnets, the stop arms gravitate to their "stop" or active position.

From the foregoing description, taken in connection with the accompanying drawings, it is thought the complete construction, operation and advantages of my invention will be readily understood by those skilled in the art to which it appertains.

What I claim is:—

1. In a track stop, supporting standards, bearings carried thereby, a substantial U-shaped stop arm journaled in said bearings and adapted to gravitate to the horizontal or active position and an electromagnetic holding mechanism adapted when energized to hold said arm in its safety position.

2. In a track stop, supporting standards, bearings carried thereby, a substantial U-shaped stop arm journaled in said bearings and adapted to gravitate to the horizontal or active position and an electromagnetic holding mechanism adapted when energized to hold said arm in its safety position, and a water shed housing supported on said standards to completely house said arm while in its safety position.

3. A track stop comprising a pair of tubular standards, bearing boxes carried thereby, bearings within said boxes; a substantially U-shaped stop arm having journals in said bearings and adapted to gravitate to the horizontal or active position, a crank arm connected with said stop arm, a solenoidal magnet and its armature mounted within one of the tubular standards, and a connection between said armature and said crank arm for holding said arm in its retracted or safety position when said solenoid magnet is energized.

4. In a track stop, a supporting structure including a pair of columns spaced apart, said columns having bearings, a stop arm, a shaft therefor having its ends journaled in said bearings, a crank on said shaft, said columns including extensions having bearings, a counter-shaft journaled in said last named bearings, cranks on said counter shaft, a connection between one of said first mentioned shaft cranks and one of said counter-shaft cranks, and a holding solenoid magnet and an armature operatively connected with another of said counter-shaft cranks.

5. A track stop comprising a supporting structure, columns depending therefrom and having bearings, a shaft journaled in said bearings, a stop arm on said shaft, a counter-shaft, an operative connection between said shafts, operating magnets and their armatures, and operating connections between said armatures and said counter-shaft.

6. A track stop comprising a supporting structure, columns depending therefrom and

- having bearings, a shaft journaled in said bearings, a stop arm on said shaft, a counter-shaft, an operative connection between said shafts, operating magnets and their armatures, and operating connections between said armatures and said counter-shaft, together with means for inclosing said connections between said shafts and between said counter-shaft and said operating magnets.
- 5 7. A track stop comprising a supporting structure, columns depending therefrom and having bearings, a shaft journaled in said bearings, a stop arm on said shaft, a counter-shaft, an operative connection between said shafts, operating magnets and their armatures, and operating connections between said armatures and said counter-shaft, together with means for inclosing said connections between said shafts and between said counter-shaft and said operating magnets.
- 10 8. A track stop comprising a supporting structure, columns depending therefrom and having bearings, a shaft journaled in said bearings, a stop arm on said shaft, a counter-shaft, an operative connection between said shafts, operating magnets and their armatures, and operating connections between said armatures and said counter-shaft, together with means for inclosing said connections between said shafts and between said counter-shaft and said operating magnets.
- 15 9. A track stop comprising a supporting structure, columns depending therefrom and having bearings, a shaft journaled in said bearings, a stop arm on said shaft, a counter-shaft, an operative connection between said shafts, operating magnets and their armatures, and operating connections between said armatures and said counter-shaft, a housing over said counter-shaft and a counter-weight on said counter-shaft above said housing.
- 20 10. A track stop comprising a supporting structure, columns depending therefrom and having bearings, a shaft journaled in said bearings, a stop arm on said shaft, a counter-shaft, an operative connection between said shafts, operating magnets and their armatures, and operating connections between said armatures and said counter-shaft, a housing over said counter-shaft and a counter-weight on said counter-shaft within said housing.
